(57) **CLAIM**

The ornamental design for a lavatory, as shown and described.

DESCRIPTION

FIG. 1 is a top, right, front perspective view of a lavatory embodying our new design;

FIG. 2 is a top plan view thereof;

FIG. 3 is a front elevational view thereof;

FIG. 4 is a right side elevational view thereof, the left side elevational view thereof being a mirror image of the right side shown;

FIG. 5 is a rear elevational view thereof;

FIG. 6 is a bottom plan view thereof;

FIG. 7 is a front sectional view thereof taken along line 7-7 of FIG. 2;

FIG. 8 is a top, right, front perspective view of a lavatory according to another embodiment of our new design;

FIG. 9 is a top plan view thereof;

FIG. 10 is a front elevational view thereof;

FIG. 11 is a right side elevational view thereof, the left side elevational view thereof being a mirror image of the right side shown;

FIG. 12 is a rear elevational view thereof;

FIG. 13 is a bottom plan view thereof; and,

FIG. 14 is a front sectional view thereof taken along line 14-14 of FIG. 9.

The broken line representations in the figures are for the purpose of illustration only, and form no part of the claimed design.
